(No Model.)

H. C. CONSTANTIN.

SHELL FISH REFRIGERATOR.

No. 382,410.

Patented May 8, 1888.

UNITED STATES PATENT OFFICE.

HENRY CHARLES CONSTANTIN, OF BROOKLYN, NEW YORK, ASSIGNOR TO HIMSELF AND HENRY J. BOOKMAN, OF SAME PLACE.

SHELL-FISH REFRIGERATOR.

SPECIFICATION forming part of Letters Patent No. 382,410, dated May 8, 1888.

Application filed October 6, 1887. Serial No. 251,668. (No model.)

To all whom it may concern:

Be it known that I, HENRY CHARLES CONSTANTIN, of the city of Brooklyn, in the county of Kings and State of New York, have invented 5 a Shell-Fish Refrigerator, of which the following is a full, clear, and exact description.

The object of my invention is to provide a receptacle for clams and oysters in the shell for use in restaurants, lunch-rooms, &c., wherein 10 they may be kept at an even cool temperature, and from which, when required, they may be readily withdrawn without the necessity of opening the doors of the receptacle.

The invention consists in the construction, 15 arrangement, and combination of parts herein-after described and claimed.

Reference is to be had to the accompanying drawings, forming a part of this specification, in which similar letters of reference indicate 20 corresponding parts in both views.

Figure 1 is a perspective view of the cooler and deliverer, and Fig. 2 is a central vertical sectional view of the same.

The body of the receptacle A is composed 25 of four wooden uprights, a, connected at about one-third their height by pairs of wooden side and end pieces, a' a'', and in said body is supported by said side and end pieces a case, B, of sheet metal, preferably zinc, having a rectangular central opening, b, and a ledge, b', at each end, said ledges being flush on their under sides with the lower sides of the side and end pieces of the frame, and from the side of 30 said central opening, b, depend sheet metal side pieces, b'', having the form of an irregular triangle, for a purpose hereinafter explained.

To the case B is adapted a box, C, having the form of an irregular triangle, constructed in two parts, c and c', respectively hinged to and 40 beneath the ledges b', and inclining downward and inward beneath the opening in the case B, the part c' of said box being longer than the part c and projecting beyond the same, as shown in Fig. 1 of the drawings. To the sides of the 45 part c' of said box are secured segmental plates c'', having slots c''' therein, in which pins c''', seated in the sides of the part c, are adapted to play.

Springs d, connected, respectively, to the lower side pieces, a', of the frame and to the 50 sides of the part c' of said box, act normally to

keep the two parts of said box closed, as shown in Fig. 1 of the drawings.

A horizontal rod, D, secured to the uprights a at one side of the frame, adds strength and support to a hanger, E, fixed above it to one of the lower side pieces of the frame, and to said hanger is pivoted at e one end of a lever, F, which projects outward at one side beneath the box C, and is provided with a handle, f. About midway of its extremities said lever is 55 connected by a hook, f', to an eye, f'', beneath the part c' of the box C. If preferred, the lever may be pivoted directly to one of the uprights or side pieces of the frame.

Within the case B are located two platforms, 60 G and H, of sheet metal, preferably zinc. The platform G has series of perforations g therein. Its sides extend upward and slightly outward, as at g', Fig. 1, so that it may be freely fitted in said case. Its body rests upon one of the 65 ledges b' and projects at a slight incline over and beyond the center of the opening in said case, as shown in Fig. 2, and to its outer edge is hinged at g'' an apron, g'', which is in turn hinged at g''' to the part c' of the box C, a suitable space being left between the lower edge of the apron and the part c' of the box. The platform H has series of perforations h therein. Its sides extend downward and rest upon the 70 other ledge, b'. Its body is hinged at h' to the 75 end of said case and projects at an incline over the platform G slightly beyond the center of the case B. Above said case is secured in any suitable manner to the uprights of the frame a rack, I, provided with slats i set upon 80 the edge and spaced apart, which rack may be strengthened, if found desirable, by diagonal cross-pieces. (Not shown.)

Upon the top of the receptacle is secured a cover, J, in which is fitted a sheet of glass, k, 85 and the sides and ends of the receptacle above the case B are provided, respectively, with double and single doors K, fitted with glass, and hinged to said frame, as shown in Fig. 1 of the drawings; or the sides and ends of the 90 receptacle may, if preferred, be provided with sliding doors fitted with glass. Said doors are provided with suitable knobs and latches for opening and securing them.

In operation the doors of the receptacle are 95

opened, ice is placed upon the rack therein, and the case is filled with clams or oysters, after which the doors are again closed. By bearing upon the handle end of the lever the parts of the box below the case are opened. The platform connected to said box is drawn down at the same time at a further incline, causing the clams or oysters to pass down over the two inclined platforms between the parts of the ⁵ ¹⁰ ¹⁵ ²⁰ ²⁵
